ULTRA HIGH FREQUENCY APPARATUS

Leonard W. Haeseler, Merchantville, and Samuel H. Watson, Audubon, N. J., assignors to Radio Corporation of America, a corporation of Delaware

Application February 24, 1943, Serial No. 476,994

9 Claims. (Cl. 179—171)

1

This invention relates generally to ultra-high frequency apparatus and more particularly to an improved circuit and apparatus for ultra-high frequency generating and amplifying systems.

Briefly, the invention comprises a tuned concentric ultra-high frequency coupling device whereby a substantially constant L/C ratio may be obtained over a relatively wide operating frequency range. It is customary to provide concentric line tuning devices for use with ultra-high frequency thermionic tubes. However, the tuning of such circuits introduces relatively serious practical difficulties since variable capacitors customarily used for this purpose also introduce objectionable inductive and resistive components. The instant invention is illustrated in combination with a conventional "light house" ultra-high frequency thermionic tube. The coupling circuits comprise three concentric cylinders coupled respectively to the cathode, the control electrode and the anode of the thermionic tube. Preferably, the length of the cylinders should be of the order of an odd multiple of a quarter wave length at the operating frequency. This length may be adjusted by providing a telescoping short-circuited section at the end of the cylinders removed from the thermionic tube. Input and output circuits may be coupled through conventional coaxial transmission lines, or any other conventional means, to suitable points on the concentric cylindrical conductors which comprise the thermionic tube circuits. Tuning of the anode circuit, for example, may be accomplished by providing a capacitive member movable along one of the concentric cylinders to provide capacitive coupling between said cylindrical member and another one of the concentric cylindrical conductors. By moving this capacitive element axially between the concentric cylindrical conductors, a substantially constant capacitive coupling may be maintained at any desired point in the circuit. The position of the lumped capacitive element may be adjusted by suitable means extending outside of the short circuiting conductive end structure remote from the thermionic tube.

Among the objects of the invention are to provide a new and improved method of and means for generating ultra-high frequency oscillations. Another object is to provide an improved method of and means for amplifying ultra-high frequency signals. A further object is to provide an improved method of and means for coupling to the operating electrodes of an ultra-high frequency thermionic tube. Still another object is

2

to provide improved ultra-high frequency thermionic tube circuit components which comprise a plurality of concentric cylindrical conducting electrodes including means for varying the electrical characteristics of the various resultant component circuits. A further object of the invention is to provide a concentric cylindrical tuning element for use in ultra-high frequency circuits whereby a substantially constant L/C ratio is obtained over a relatively wide frequency tuning range.

The invention will be described in greater detail by reference to the accompanying drawing of which Figure 1 is a cross-sectional elevational view of a preferred embodiment thereof; Figure 2 is a cross-sectional fragmentary view of a modification of the embodiment illustrated in Figure 1; and Figure 3 is a schematic circuit diagram of the equivalent electrical circuit of the devices illustrated in Figures 1 and 2. Similar reference numerals are applied to similar elements throughout the drawing.

Referring to Figure 1, an ultra-high frequency thermionic tube of the "light house" type such as, for example, the RCA type GL-446, includes a cathode 1, a control electrode 2 and an anode 3. The operating potentials for the cathode and control electrode may be provided in any conventional manner, not shown. Three concentrically disposed cylindrical conductive elements 4, 5 and 6 comprise coaxial tuning elements which form the thermionic tube coupling circuits. One end of the first conductive element 4 is connected to the cathode 1. One end of the second conductive element 5 is connected to the control electrode 2 and the corresponding end of the third conductive element 6 is connected through a small capacitor 7, having a mica or other suitable dielectric, to the anode 3. The remaining ends of the concentric conductors 4, 5 and 6 are telescoped with similar conductive elements 14, 15 and 16 which terminate in a short-circuiting plate 11, which may be considered to be at ground potential. The telescoping sections of the concentric coupling device are adjusted to provide a length of the order of an odd multiple of one quarter wave length at the operating frequency. A shorting plug 20, which may be operated externally by an adjusting knob 21, may be provided for adjusting the length of the inner line 6 independently of the intermediate and outer lines 5 and 4, respectively, in order to compensate for differences in tube inter-electrode capacitances.

55 A fourth cylindrical conducting element 8,

which includes a spring member 9, surrounds a portion of the third conducting elements 6, and is in electrical contact therewith. The outer face 10 of the fourth conducting element 8 provides capacitive coupling with the inside surface of the second concentric conducting element 5. The resulting capacitive coupling provides a lumped capacity between the corresponding circuit elements. This lumped capacity may be provided at any desired point in the coupled circuits by moving the fourth conductive element 8 axially between the conductive elements 5 and 6 by means of tuning rods 11 and 12 which extend outside of the conductive plate 17 at a point remote from the thermionic tube. Preferably, the tuning rods 11 and 12 are connected together by a suitable conductive member 13 to provide a conventional adjusting member. Anode potential may be supplied by a lead through the interior of the inner conductive element 6 in any conventional manner. Preferably this circuit should include an isolating impedance device such as a reactance coil 18 and/or a resistor 19.

If the circuit is to be used as an amplifier, input signal potentials may be applied to predetermined points on the two outer cylindrical conductive elements 4 and 5 to provide suitable impedance matching to the driver circuit. Output potentials may be derived from suitable points on the intermediate and inner concentric conductive elements 5 and 6, respectively, to provide suitable output impedance matching.

If the circuit is to be adapted to the generation of the ultra-high frequency oscillations, the input connections may be omitted and the circuit components varied to provide suitable reaction therefor.

Figure 2 is a fragmentary cross-sectional view of the device described in Figure 1 wherein the adjustable capacitive element comprises a cylindrical insulating member 22 having a relatively high dielectric constant, such as, for example, polystyrene. The position of the capacitive element may be adjusted axially between the conductive elements 5 and 6 as described heretofore. This modification provides the advantage of absence of sliding contacts which would introduce noise in receiver circuits.

Figure 3 represents the equivalent electrical circuit for the amplifying device described in Figure 1. It should be noted that the effect of adjusting the position of the capacitive element 8 is effectively to couple a fixed capacitor to predetermined points in an inductive circuit coupling the anode and control electrodes of the thermionic tubes. The effect of varying the position of the input terminals on the two outer concentric conductors 4 and 5 is to couple the input circuit to predetermined portions of the inductive circuit connecting the cathode 1 with the control electrode 2 of the thermionic tube.

It should be understood that the capacitive element 8 may be similarly adapted to tune other desired thermionic tube circuits and that a plurality of such capacitive elements may be provided for simultaneous adjustment of the operating characteristics of a plurality of such circuits.

Thus the invention described comprises a novel tuning device for the purpose of coupling ultra-high frequency thermionic tube electrodes for generating or amplifying ultra-high frequency currents.

We claim as our invention:

1. An ultra-high frequency circuit which in-

cludes a thermionic tube having at least a cathode electrode, a control electrode and an anode electrode, a plurality of concentric cylindrical conductive elements, means connecting one end of a first of said elements to one of said tube electrodes, means connecting one end of a second of said elements to another of said tube electrodes, conductive means connecting together the remaining ends of said elements, a movable capacitive element in operative relation to said first and second conductive elements, means for adjusting the position of said capacitive element with respect to said conductive elements for tuning said circuit, means connecting one end of a third of said conductive elements to a third of said tube electrodes, and means connecting the remaining end of said third conductive element to said remaining ends of said first and said second conductive elements.

2. An ultra-high frequency circuit which includes a thermionic tube having at least a cathode electrode, a control electrode and an anode electrode, a plurality of concentric cylindrical conductive elements, means connecting one end of a first of said elements to one of said tube electrodes, means connecting one end of a second of said elements to another of said tube electrodes, conductive means connecting together the remaining ends of said elements, a movable capacitive element in operative relation to said first and second conductive elements, means for adjusting the position of said capacitive element with respect to said conductive elements for tuning said circuit, means connecting one end of a third of said conductive elements to a third of said tube electrodes, and means connecting the remaining end of said third conductive element to said remaining ends of said first and said second conductive elements.

3. An ultra-high frequency circuit which includes a thermionic tube having at least a cathode electrode, a control electrode and an anode electrode, a plurality of concentric cylindrical conductive elements, means connecting one end of a first of said elements to said control electrode, means connecting one end of a second of said elements to said anode, conductive means connecting together the remaining ends of said elements, a movable capacitive element in operative relation to said first and second conductive elements, and means for adjusting the position of said capacitive element with respect to said conductive elements for tuning said circuit.

4. An ultra-high frequency circuit which includes a thermionic tube having at least a cathode electrode, a control electrode and an anode electrode, a plurality of concentric cylindrical conductive elements of the order of a predetermined odd multiple of a quarter wave in length, means connecting one end of a first of said elements to one of said tube electrodes, means connecting one end of a second of said elements to another of said tube electrodes, conductive means connecting together the remaining ends of said elements, a movable capacitive element in operative relation to said first and second conductive elements, means for adjusting the position of said capacitive element with respect to said conductive elements for tuning said circuit, means connecting one end of a third of said conductive elements to a third of said tube electrodes, and means connecting the remaining end of said third conductive element to said remaining ends of said first and said second conductive elements.

5. Apparatus of the type described in claim 4 including a source of input signals, and means for coupling said source to predetermined points on a predetermined pair of said conductive elements.

6. An ultra-high frequency circuit which includes a thermionic tube having at least a cathode electrode, a control electrode and an anode electrode, a plurality of concentric cylindrical conductive elements, means connecting one end of a first of said elements to one of said tube electrodes, means connecting one end of a second of said elements to another of said tube electrodes, conductive means axially movable along said conductive elements connecting together the remaining ends of said elements, a movable capacitive element in operative relation to said first and second conductive elements, means for adjusting the position of said capacitive element with respect to said conductive elements for tuning said circuit, means connecting one end of a third of said conductive elements to a third of said tube electrodes, and means connecting the remaining end of said third conductive element to said remaining ends of said first and said second conductive elements.

7. Apparatus of the type described in claim 1 including means movable axially along a second predetermined pair of said conductive elements for deriving energy therefrom.

8. Apparatus of the type described in claim 1 characterized by the fact that said capacitive element is a cylindrical insulating material having a relatively high dielectric constant.

9. An ultra-high frequency circuit which in-

cludes a thermionic tube having at least a cathode electrode, a control electrode and an anode electrode, a plurality of concentric cylindrical conductive elements, means connecting one end of a first of said elements to one of said tube electrodes, means connecting one end of a second of said elements to another of said tube electrodes, annular conductive means connecting together the remaining ends of said elements, a movable capacitive element in operative relation to said first and second conductive elements, means for adjusting the position of said capacitive element with respect to said conductive elements for tuning said circuit, means connecting one end of a third of said conductive elements to a third of said tube electrodes, and means connecting the remaining end of said third conductive element to said remaining ends of said first and said second conductive elements.
